RASCHEL KNITTING MACHINE

Karl Kohl, Hainstadt (Main), Germany, assignor to Karl Mayer Erste Hessische Wirkmaschinenfabrik G.m.b.H., Obertshausen, Germany

Filed Aug. 8, 1958, Ser. No. 753,978

Claims priority, application Germany Aug. 10, 1957
3 Claims. (Cl. 66—86)

The present invention relates to double-rib looms or 10 Raschel type knitting machines.

As is known, fast operating Raschel machines require detents for preventing the needle latches from closing after the knitted loops glide off the latches. It has been proposed to use a wire in the bedplate of the comb or a special bar rigidly connected with the comb to serve as a detent means for the knitting needle latches. In such structures, the comb carrying the latch detent means must go through several motions during a single operating cycle, which interferes with an increase in the machine speed and subjects the parts to considerable wear. Furthermore, in the case of Raschel machines with a plurality of yarn guides, which are used to knit elastomer threads or yarns, the known latch detents have deflected or bent the outer elastic yarns, causing yarn damage or operating difficulties.

It is the primary object of the present invention to overcome these disadvantages of the prior art and to provide novel knitting needle latch detent means in Raschel type knitting machines.

I accomplish this and other objects by providing a thin sheet, web or pin in each knitting needle plane to serve as needle latch detent. Throughout this specification and the claims, the generic term "web" detent is designed to cover any thin detent member which may be arranged in the plane of a knitting needle to catch the needle latch and prevent it from closing while it is engaged by the web.

The detent webs of the invention may be arranged on a separately controlled support bar.

Since the detent webs are positioned between the yarns and the straight line of the yarn path from each yarn guide to the shaft of its associated latch needle is thus not interrupted, the outer yarns will not be deflected or bent even in the case of machines with a great number of yarn guides. Furthermore, such detent webs make it possible to reach to the inner-most point of the latch, even if a comb is used, so that any undesirable movement of the latch is prevented as soon as the latch is freed from the yarn loop gliding therefrom. Also, the movement of the comb or the support bar for the detent webs per operating cycle is simplified by this arrangement so that the speed of the machine may be considerably increased.

The novel needle latch detents means of the present invention may be mounted above or below the support bar for the needle guide comb and the detent webs may interdigitate with the guide comb so that the detent reaches as closely to the innermost point of the latch as possible.

The above and other objects, features and advantages of the invention will be more fully set forth in the following detailed description of certain preferred embodiments thereof, taken in conjunction with the accompanying drawing wherein

FIG. 1 is an end view partly in section of the apparatus of FIG. 2;

FIG. 2 is a front view of the Raschel type knitting machine according to the invention;

FIG. 3 is a perspective view of the yarn loop forming portion of the knitting machine, on an enlarged scale;

2

FIG. 4 schematically shows another embodiment of the needle latch detent means of the invention; and

FIG. 5 is a schematic top view of the yarn loop forming portion of the machine.

Referring now to FIGS. 1 and 2, the knitting machine is shown to be supported on a housing 1. Electrical driving motor 2 is mounted in brackets 3 on the bottom plate 4 of the housing at one side of the machine. Motor shaft 5 is coupled to the cam shaft 7 at 6 while the opposite motor shaft portion 8 carries driving wheel 9 for the driving chain 10. Groups of cams 11, 12, 13 and 14 are keyed to shaft 7, only one such group being shown in FIG. 2 but a plurality of like cam groups being mounted along the entire length of shaft 7. Push rods 15, 16, 17 and 18 are mounted in engaging cooperation with respective cams 11, 12, 13 and 14, being connected at their opposite ends to respective guide members of the knitting machine, as is known per se, to actuate the knitting cycle.

20 The latch or knitting needle supporting bar 19 carries a downwardly directed support 20 threadedly connected with rod 15 at 21.

Support 20 glides in a cylinder 22 which has a flange 23 bolted to housing cover 25 at 24. The cover is apertured at 26 to permit rod 15 to pass through the cover into the cylinder and up to the support 20. An upwardly directed arm 27 is mounted on the cylinder to support a needle trick plate 28 at its upper end. The trick plate is stationary.

30 Push rods 16 and 17 are actuated by cams 12 and 13, respectively, engaging at their other ends lever arms 29 and 30 respectively. Lever arm 29 forms a two-armed lever with arcuate arm 32 and lever arm 30 forms a two-armed lever with arcuate arm 33, both two-armed levers being mounted on pivot axle 31. Arm 32 carries bar 34 at its free upper end and bar 35 is carried by the free upper end of arm 33.

As is shown most clearly in FIG. 3, bar 34 carries the latch detent webs 36 while bar 35 carries the webs 37 of the needle guide comb.

40 Push rod 18 is actuated by cam 14 and engages the upper lever 38 at 39. At its opposite end, the lever 38 is connected to shaft 41 which is rotatably journaled in bearing 40. Shaft 41 carries a plurality of downwardly directed support elements 42 which carry arcuate members 43. As best shown in FIG. 3, the bars 44 which carry the yarn guides 45 are mounted on members 46 which are slidably supported on the arcuate members 43. The members 46 are interconnected by longitudinal rails 47 and 48, upper rail 48 having the form of an angle iron. The longitudinal rails 47 and 48 glide in notches 49 of arcuate member 43 and are interconnected at one end by cross connecting piece 50. Horizontal push rods 52 are threadedly connected to the cross connecting pieces at 51 while the other end of the push rods is linked at 53 to lever 54. Lever 54 is journaled in bracket 56 on housing cover 25, its pivot being shown at 55. Since there are four needle supporting bars 44, there are provided four actuating links 52, 54 which are positioned one behind the other so that only one actuating linkage is seen in FIG. 2. Levers 54 carry dogs 55 which engage the four adjacent wheels 56. The wheels 56 are keyed to axle 57 which carries a beveled gear 58 engaging beveled gear 59 mounted on axle 60. Axle 60 is supported on the housing cover 25 by bearing 62 and carries at its outer end toothed wheel 61 for chain 10.

55 The bearings 40 for shaft 41 are fixed to support tube 63 which is supported by end walls 64 on both sides of the machine, only one of the two like end walls being shown in FIG. 2. The end walls are bolted to housing 1 at 65 and include an upper plate 64a which carry the shafts 66 holding warp beams 67. As shown in FIG. 1,

the yarns 68 and 69 run from the beams 67 over guide plate 70 through apertures 71 in rails 48 and through the eyes in yarn guides 45 to the loop forming latch needles. The knitted fabric 72 then runs over rolls 73 and 74 to storage beam 75.

As shown in FIG. 1, the yarn guides 70 are resilient members riveted at 76 to longitudinal strips 77 which, in turn, are carried by transverse yoke 78 mounted on the support tube 63 by means of angle iron 79 and threaded bolts 80 and 81.

As shown in FIG. 1, the lower ends of push rods 15, 16, 17 and 18 are linked to respective arms 83 of two-armed levers 82, the joint 84 engaging a respective one of cams 11, 12, 13 and 14 while the other arm 85 of the two-armed levers, which forms an acute angle with the first-named arm thereof, also engages the cam surface so as to prevent disengagement of the push rod ends from the cam surfaces. The two-armed levers are pivotally mounted on shaft 86 which is journaled in housing 1, as indicated in FIG. 2, where the shaft 86 is shown mounted in wall 88 which has an aperture 87 through which shaft 7 extends.

Enlarged FIG. 3 clearly shows the novel latch detent webs 36 mounted on bar 34 while the comb webs 37 are mounted on bar 35. The comb webs are shown to pass through the interspacers between the knitting needles 89 (see also FIG. 5), the needles being mounted on bar 19. In this phase of the knitting operation, as illustrated in FIG. 3, the detent webs 36 have been moved with their front ends into the range of needle latches 90 so as to prevent the latches from moving upwardly. As can be clearly seen in FIG. 5, the detent webs 36 pass between the comb webs 37 and are positioned substantially in the same plane as the respective needle shafts 89. It is clear that the detent webs 36 do not come into contact with yarns 69 so that the path of the yarns from yarn guides 45 to knitting needles 89 is unimpeded.

As is shown in FIG. 4, the arrangement is not limited to that shown in FIG. 3. Thus, in the embodiment of FIG. 4, the support bar 34' for the latch detent webs 36' is positioned below the support bar 35' extend toward the comb webs 37' and the detent webs of the comb from below.

While the invention has been described and illustrated in connection with certain now preferred embodiments, it will be clearly understood that many modifications and variations may occur to the skilled in the art, particularly after benefiting from the present teaching, without departing from the spirit and scope of the present invention as defined in the claims. More particularly, any conventional driving mechanism may be used to time the move-

ment of the various knitting parts during a knitting cycle, as well understood in the art, and any individual latch detent means equivalent to a web, pin or like member may be used.

5. What I claim is:

1. In a Raschel knitting machine having a plurality of yarn guides, and a plurality of knitting needles juxtaposed and spaced from each other in a predetermined direction, each knitting needle having a shaft and a latch pivoted to said shaft for movement in a plane transverse of said direction; a comb including a bar member and a plurality of comb webs mounted on said bar member in interdigitating relationship with said knitting needles; latch detent means comprising a support, a plurality of detent webs mounted on said support, said webs longitudinally extending in respective ones of said planes and being spaced from each other in said predetermined direction, and actuating means for actuating movement of said support and of said bar member relative to each other and relative to said needles in timed sequence, said support being moved toward and away from a position of engagement of said detent webs with respective ones of said latches.

2. In a Raschel knitting machine having a plurality of 25 yarn guides, and a plurality of knitting needles juxtaposed and spaced from each other in a predetermined direction, each knitting needle having a shaft and a latch pivoted to said shaft for movement in a plane transverse of said direction; a comb including a bar member and 30 a plurality of comb webs mounted on said bar member in interdigitating relationship with said knitting needles, latch detent means comprising a support mounted above said bar member, a plurality of detent webs mounted on said support, said webs longitudinally extending in respective ones of said planes and being spaced from each other in said predetermined direction, and actuating means for actuating movement of said support toward and away from a position of longitudinal abutting engagement of said detent means with respective ones of said latches.

3. In a Raschel knitting machine of claim 1, said support being mounted below said bar member.
